UNITED STATES PATENT OFFICE.

FRANCISCO DE A. DEL VALLE ATILES, OF SAN JUAN, PORTO RICO.

TELEGRAPH TRANSMITTING-MACHINE.

1,027,376.

Specification of Letters Patent.

Patented May 21, 1912.

Application filed December 19, 1911. Serial No. 666,677.

To all whom it may concern:

Be it known that I, FRANCISCO DE A. DEL VALLE ATILES, a citizen of the United States, residing at San Juan city, Porto Rico, have 5 invented new and useful Improvements in Telegraph Transmitting-Machines, of which the following is a specification.

Electrically transmitted messages ordinarily sent by means of a code system generally require the manipulation of a transmitting key, the same being manipulated for the most part by means of a skilled operator. It frequently happens and occasions 10 arise where messages are desired to be sent and the services of a skilled operator are 15 not available and for lack of communication disaster oftentimes results.

This invention provides a mechanism which will admit of a message being transmitted by a code system without requiring the services of a skilled operator, the average person being enabled to transmit the message since the only skill required is the 20 selection of keys bearing letters and other 25 characters and depressing said keys, thereby bringing into operation an actuator which is associated with a transmitting key whereby the desired letters are transmitted to 30 form words which convey the desired information.

The machine embodies a plurality of character wheels each embodying a number of contacts, brushes arranged to coöperate with the character wheels for closing a circuit including an actuator for operating the transmitting key, and a plurality of manually operable keys for actuating the character wheels, whereby the transmitting key actuator is operated in substantially the 35 same manner as when manipulated by the skilled operator.

The invention consists of the novel features, details of construction and combination of parts, which hereinafter will be 40 more particularly set forth, illustrated in the accompanying drawings, and pointed out in the appended claims.

Referring to the drawings, forming a part of the specification, Figure 1 is a top plan view of a transmitting machine embodying the invention. Fig. 2 is a side view of the electrically operated transmitting key actuator. Fig. 3 is a side view of one of the 45 keys, a character wheel and intermediate 50 connections. Fig. 4 is a front view of the

part shown in Fig. 3. Fig. 5 is a top plan view of the part shown in Fig. 3. Fig. 6 is a detail view of one of the character wheels.

Corresponding and like parts are referred to in the following description, and indicated in all the views of the drawings, by the same reference characters.

The machine embodies an electrically operated transmitting key actuator A and a bank of keys B, one being provided for each letter, number, punctuation and other character used in transmitting messages electrically. Each key is provided with a mark corresponding with the character to be transmitted when the key is operated, thereby enabling the proper keys to be readily selected by the average person when it is required to transmit a message. A character wheel C is had for each key. In general construction the character wheels are similar, but each is adapted to transmit a different character according to the code system employed and which in the present instance consists of dots and dashes. Each of the keys B is carried by a lever 1, which is pivoted intermediate of its ends to an upright 2. Springs 3 and 4 are located upon opposite sides of the fulcrum of the key lever 1 and are interposed between it and the base 5, the tension of said springs being regulated by set screws to insure a uniform touch. A guide 6 is had for each key lever and is preferably located near the key so as to resist any tendency of the key to move laterally. A 70

stop 7 limits the movement of the key in one direction and holds it in normal position. The stop 7 is arranged near the inner or rear end of the key lever. A second lever 8 is pivoted between its ends to an arm 9 rising from the base 5. A link 11 connects the outer end of the lever 8 with the inner end of the lever 1. A spring 12 supplements the action of the springs 3 and 4 in returning the parts to normal position. A lever 13 pivotally supported midway of its ends in line with the axis of a character wheel has one end connected by means of a link 14 with the rear end of the lever 8. The opposite end of the lever 13 is provided with a spring actuated dog 15, which coöperates with a ratchet wheel 16 connected with the character wheel so as to turn the lever when the key is depressed. A detent 17 pivotally con- 110

nected at one end to the upright 10 is adapted to engage the teeth of the ratchet wheel 16 to prevent backward rotation thereof.

- Each character wheel is provided with a number of contacts corresponding with the character to be transmitted and the ratchet wheel 16 has a number of teeth corresponding with the number of characters provided upon each of the character wheels. In the present instance each of the character wheels has four sets of contacts corresponding to four characters and the ratchet wheel 16 has four teeth. The parts are so constructed, proportioned and arranged that when a key B is depressed the ratchet wheel 16 is moved a distance corresponding to a tooth, thereby advancing one of the characters so as to bring the next character or set of contacts in position for operation when the key is next depressed. A brush 18 is pivotally connected to the upright 10 and has a binding screw 19 for securing a conducting wire thereto. The brush 18 is arranged to bear upon the outer edge of the character wheel. A second brush 20 is pivotally connected to the upright 10 and has a binding screw 21 to admit of a conducting wire being connected therewith. The brush 20 engages an annular contact 22 forming a part of or connected with the character wheel. Each of the character wheels is provided upon its outer edge with a number of contacts which are spaced apart in the path of the brush 18, the spaces receiving an insulating material which prevents the brush entering the spaces and obstructing the movement of the character wheel. The contacts are electrically connected with one another and with the annular contact 22. The outer edge of each character wheel is smooth or continuous and comprises metal contact pieces separated by insulating material so that in the rotation of the character wheel the circuit is made and broken corresponding to the nature of the contacts and the spaces formed between them, the contacts of each group corresponding to a character are long and short and indicate dots and dashes of the Morse system or other code used in telegraphic communication. The contacts of each group are arranged according to the character represented thereby so that when the wheel is operated electric impulses are transmitted similar to those imparted by the telegraphic transmitting key when operated by the skilled operator in transmitting a message. It is to be understood that the brushes 18 and 20 form elements of an electric circuit which is controlled by the character wheel, it being further understood that each character wheel controls a local circuit including the electrically operated transmitting key actuator so that when a key B is depressed the character represented thereby is transmitted electrically to the ac-

tuator A and which actuator in turn operates the transmitting key so as to send the character over the main line.

The electrically operated transmitting key actuator A in its simple form consists of an electro-magnet 23 and an armature 24, the latter being pivoted at 25 to an upright and held away from the core of the electro-magnet by means of a spring 26. The electro-magnet illustrated is of the two coil type and is mounted upon a base 27, which in turn is secured to the base 5. The armature 24 is extended and is provided at its outer end with a set screw 28 to which is attached a button 29 forming a pressure piece to engage the transmitting key 30 of the main line. The button 29 is of rubber or similar yieldable material and is connected with the set screw 28 by means of a ball and socket joint. The electro-magnet is included in the circuit which includes all the character wheels and the circuit closing devices co-operating therewith so that upon operating any one of the keys B the armature 24 is actuated in a manner to correspond with the character represented by the key being depressed, with the result that the transmitting key 30 is actuated and caused to transmit the character represented by the key depressed.

All the brushes 20 are electrically connected by means of a wire 31 and all the brushes 18 are electrically connected by means of a wire 32. The wires 31 and 32 include the coils of the electro-magnet 23 and the circuit represented thereby also includes a current generator of any type. When a message is to be transmitted the keys B are depressed according to the characters and words to be transmitted, a character wheel being operated each time a key is depressed, thereby producing impulses in the electro-magnet corresponding with the selected character, thereby actuating the armature 24, which in turn actuates the transmitting key 30.

The number of characters to each wheel C will depend upon the size of the wheel but the parts are of such construction and arrangement that each movement of a character wheel causes the contacts corresponding to the character to pass beneath the brush 18, thereby setting up impulses in the circuit including the electro-magnet 23 to operate the armature 24 in consonance with the impulses required to properly operate the transmitting key 30 according to the letter or character to be transmitted.

From the foregoing description, taken in connection with the accompanying drawings, the advantages of the construction and of the method of operation will be readily apparent to those skilled in the art to which the invention appertains, and while I have described the principle of operation of the

invention, together with the device which I now consider to be the embodiment thereof, I desire to have it understood that the device shown is merely illustrative, and that such changes may be made when desired as are within the scope of the claims appended hereto.

Having thus described the invention what is claimed as new, is:—

- 10 1. In a telegraph transmitting machine, the combination of an electrically operated transmitting key actuator, the same consisting of an electro-magnet and an armature, a plurality of mechanisms included in a circuit with said electro-magnet for producing impulses corresponding with the characters to be transmitted, a set screw carried by the armature of the aforesaid electro-magnet, and a pressure piece of yieldable material
15 connected with the set screw by means of a
20

ball and socket joint and adapted to engage the telegraphic transmitting key.

2. In a machine of the character described, the combination of a character wheel, a ratchet wheel connected with the character wheel to turn therewith, a lever mounted in line with the ratchet wheel and character wheel and provided with a dog to engage the teeth of the ratchet wheel, a second lever having one of its arms connected with the arm of the first mentioned lever, a key lever, and a link connecting the key lever with the said second lever.

In testimony whereof I affix my signature in presence of two witnesses.

FRANCISCO DE A. DEL VALLE ATILES.
